UNITED STATES PATENT OFFICE.

ABRAHAM SHORT AND DAVID SHORT, OF WEST LIBERTY, OHIO.

IMPROVEMENT IN LOUNGES.

Specification forming part of Letters Patent No. **56,809**, dated July 31, 1866.

To all whom it may concern:

Be it known that we, ABRAHAM SHORT and DAVID SHORT, of West Liberty, in the county of Logan and State of Ohio, have invented a new and useful Improvement in Lounges; and we do hereby declare that the following is a full, clear, and exact description thereof, which will enable others skilled in the art to make and use the same, reference being had to the accompanying drawings, forming part of this specification, in which—

Figure 1 is an end elevation of our invention. Fig. 2 is a rear or back view of Fig. 1. Fig. 3 is a view showing the device with its back turned down to a horizontal position.

Similar letters of reference indicate like parts.

Our invention relates to an improvement in that class of lounges whose backs can be lowered to form a bed.

A designates the seat of the chair, which is mounted on rockers *aa* in the usual manner, except, perhaps, that the rockers are a little longer than they would be ordinarily. A' designates the back of the chair. (See Figs. 1 and 2.) This is joined to a seat by a rod, *b*, passing through its lowest extremity and through the seat also, and this permits the back to be raised or lowered to form a chair or couch, as the case may be. The back A'' is so stuffed that when it is thrown down it will throw up the stuffing on its lower edge so as to bring it on a level with the stuffing of the seat, as shown in Fig. 2 at 3, and this is a matter of considerable importance, for in this case the cushion and back need not be removable, nor will there be any necessity for providing a roll of stuffing to place in the crack between the seat and back, which is formed when the back and seat are connected, as heretofore.

To each rocker *a*, near its outer end, there

is pivoted a short leg, C, and to the loose end of these legs there are connected the respective ends of a rod, D. This rod commences, say, at one leg C, and extends vertically up to the back of the chair, where it is secured by a staple, *e*; thence horizontally along the back to the side opposite where it commenced, where another staple, *e'*, secures it; thence down to the other leg, all of which will be understood by reference to Fig. 2.

When the back is to be let down to form a couch it will be noticed that the rod D causes the lower ends of the pivoted legs C to turn outward so that they will rest upon the floor; hence the rocking capacity of the chair is at once overcome, and the seat and back are brought on a level with each other.

The back of the chair is held braced up by a transverse rod, E, whose lower ends are pivoted to the rockers. This rod serves as a pawl operating on both arms of the rod D. When the back is raised and the rod E is thrown forward it drops into notches *e* cut in the arms of the rod D, and consequently keeps the back braced up.

Springs *f* may be employed for keeping the pawl E pressed toward the rod D, if desired.

It will be noticed that the mechanism for operating the back is simple in every respect, and not liable to get out of order.

What we claim as new, and desire to secure by Letters Patent, is—

The combination of the leg C, rod D, and pawl-rod E with the back A', for adjusting the position of the latter, substantially as shown and described.

ABRAHAM SHORT.
DAVID SHORT.
